UNITED STATES PATENT OFFICE.

OTTO HASSELMANN, OF WIESBADEN, GERMANY.

SURGICAL INSTRUMENT FOR CUTTING BANDAGES.

989,255.

Specification of Letters Patent. Patented Apr. 11, 1911.

Application filed June 29, 1910. Serial No. 569,588.

To all whom it may concern:

Be it known that I, OTTO HASSELMANN, a subject of the German Emperor, and resident of Wiesbaden, Germany, have invented 5 certain new and useful Improvements in Surgical Instruments for Cutting Bandages, of which the following is a specification.

This invention relates to an improved surgical instrument by which bandages can 10 be cut open after their use in a handy and easy way.

The accompanying drawing shows the improved instrument.

Figure 1 is a side view of the same, Fig. 15 2 a top view thereof, the cutter being omitted, Fig. 3 shows the screw for fixing the cutter, which is shown separated in Fig. 4. Fig. 4 is a side elevation of the cutter.

The instrument comprises a lever 1 which 20 is slightly bent near its front end. Between said bend 2 and its front extremity, said lever carries an elongated slot 3, in which a cutter 4 can be fixed by means of a screw 5 in such a way that it projects from the underside of the lever and lies with its cutting 25 edge toward the front extremity of the lever. Said front extremity is flattened, as shown in Fig. 2, and provided with an upturned gripping portion 6, as shown in 30 Fig. 1.

For using the instrument the cutter is shifted beneath a bandage and an upward pressure is exerted on the rear end of the lever, the front extremity of the lever then firmly gripping the bandage, whereby the 35 knife can cut the same, the lever being then shifted with its knife along the cut just made, for further cutting in the way described.

The knife 4 can be also reversed or turned 40 in the lever so that its cutting edge projects to the rear, to suit any requirements.

I claim:—

A surgical instrument for cutting bandages after their use, comprising a lever 45 having a flattened front end and a slight bend near the same, a detachable knife projecting from the underside of said lever and located between said bend and front end, and an upturned gripping portion at the 50 front extremity of said lever, for the purpose set forth.

In testimony whereof, I have hereunto set my hand in the presence of two subscribing witnesses.

OTTO HASSELMANN.
